UNITED STATES PATENT OFFICE.

JOSEPH B. EAGLESTON, OF ORIENT, OHIO, ASSIGNOR OF ONE-HALF TO ADIN MARTINO,
OF ORIENT, OHIO.

BROOM-SEWING NEEDLE.

1,118,190.

Specification of Letters Patent. Patented Nov. 24, 1914.

Application filed April 20, 1914. Serial No. 833,027.

To all whom it may concern:

Be it known that I, JOSEPH B. EAGLESTON, a citizen of the United States, residing at Orient, in the county of Pickaway and State 5 of Ohio, have invented a certain new and useful Improvement in Broom-Sewing Needles, of which the following is a specification.

The object of this invention is to provide 10 an improved device of simple construction for sewing brooms whereby among other advantages time is saved in the manipulation of the cord.

The invention is embodied in the construction 15 herein shown and described, the feature of novelty being claimed at the end of the description.

In the accompanying drawing—Figure 1 is a view in side elevation showing the handle 20 in longitudinal section. Fig. 2 is a similar view showing the position of the parts when the needle has been pushed or thrust with a thread through a broom. Fig. 3 illustrates the position of the parts after the 25 needle has drawn a thread from the opposite side of the broom. Fig. 4 is an end view of the needle and thread clamping sleeve thereon.

In the views 5 designates the needle which 30 is mounted fixedly on one end of a suitable hollow handle 6. The needle consists of a thin flat blade pointed at its free end and having a dove-tailed notch or "eye" 5^a in one edge near its pointed end.

35 7 designates a sleeve which I denominate a clamp or grab, said sleeve being slidable upon the needle. This sleeve 7 is provided with a stem 8 that extends through the handle and a stop plate 9 on the rear end of the 40 handle said stem being provided at its extremity with a stop button 8^a to abut against the plate 9 to limit the outward thrust of the sleeve. In the cavity of the handle is a coil spring 10 that abuts at one end against the 45 plate 9 and at the other end against a button 8^b on the stem. The spring 10 tends normally to press the sleeve forward on the needle so as to close the eye thereof, the position of the stop button 8^a determining

50 such eye-closing position when the parts are free. The sleeve 7 has at that side which passes next the notch a forwardly projecting nose as seen at 7^a to overreach a thread

laid in the eye and press the same toward the forward corner of the eye. This construction also tends to prevent accidental removal of the thread.

11 designates a yoke on the rear end of the handle to form a guard to prevent interference with the operation of the stem. 60

In Fig. 2 is illustrated how a thread is pushed through a broom to be sewed. In this operation the rear wall of the eye acts on the thread.

In Fig. 3 is depicted how a thread is 65 drawn from the opposite side of the broom. In pushing the thread through the broom the sleeve is obstructed or stopped by the face of the broom, as shown in Fig. 2, and the thread is easily removed to be placed in 70 the eye after the needle has been thrust through a fresh place in the broom but without thread. When, however, a thread is drawn through the broom, as last stated, the sleeve automatically grabs or clamps 75 the loop of the thread upon its emergence from the broom and the same is ready for a further pushing through as seen in Fig. 2. In this construction the thread is clamped as it is drawn from the broom whatever be 80 the thickness of the thread.

The parts are susceptible of modification as to form without departing from the gist of the invention as claimed.

What I claim is:

1. A broom sewing device comprising, in combination, a needle having a thread-receiving eye, a clamping sleeve slidable on the needle, and a spring tending normally to move the sleeve into thread clamping position. 85

2. A broom sewing device comprising, in combination, a handle, a needle mounted thereon, said needle having a thread-receiving eye, a clamping sleeve slidable on the 95 needle, and a spring tending normally to move the sleeve into thread clamping position.

3. A broom sewing device comprising, in combination, a hollow handle, a needle mounted thereon, said needle having a thread-receiving eye, a clamping sleeve slidable on the needle, and a spring in the cavity of the handle normally actuating the sleeve to move the same into thread clamp- 105 ing position.

4. A broom sewing device comprising, in combination, a needle having a thread-receiving eye with an upwardly and rearwardly inclined wall, a clamping sleeve sliding on the needle and a spring tending normally to move the sleeve into thread clamping position, said sleeve having a nose co-

operating with said upwardly and rearwardly inclined wall.

JOSEPH B. EAGLESTON.
